R. H. ROGERS.

BEAM OR LIKE STRUCTURAL MEMBER FOR USE IN REINFORCED CONCRETE
CONSTRUCTION AND OTHER PURPOSES.

APPLICATION FILED NOV. 17, 1920.

1,433,232.

Patented Oct. 24, 1922.

UNITED STATES PATENT OFFICE.

RICHARD HAWKE ROGERS, OF PADDINGTON, LONDON, ENGLAND.

BEAM OR LIKE STRUCTURAL MEMBER FOR USE IN REINFORCED CONCRETE CONSTRUCTION AND OTHER PURPOSES.

Application filed November 17, 1920. Serial No. 424,647.

To all whom it may concern:

Be it known that I, RICHARD HAWKE ROGERS, a subject of the King of England, residing at Paddington, London, England, have invented certain new and useful Improvements in Beams or like Structural Members for Use in Reinforced Concrete Construction and Other Purposes, of which the following is a specification.

- 10 This invention relates to beams and other structural units of a like kind, that is to say made of metal and intended to be so used that when loaded they are subjected to a bending moment. An unit according to 15 this invention is intended primarily to take the place of centering in the formation of reinforced concrete floors and moreover to combine the functions of centering and reinforcement. This invention is, however, not 20 confined to the said object. For example the unit referred to may be employed in the building of walls or for doors or may be employed alone wherever a beam is ordinarily employed.
- 25 The present invention provides a beam or like structural unit as hereinbefore described formed of two metal plates arranged face to face and perforated to provide tongues which said tongues are directed towards the 30 opposed plate and are secured to one another or to the opposed plate.
- Further, according to this invention, the tongues of one plate at least are so formed from the material of the plate as to leave 35 therein one or more substantially continuous strips extending lengthwise of the unit and other strips extending transversely from the first said lengthwise strip or strips.
- The said transversely extending strips 40 may be arranged to constitute ties between two of the said lengthwise extending strips that are adjacent to one another.
- Conveniently, according to this invention, 45 the said tongues are so formed that at least one of the said lengthwise strips has along both its edges tongues attached thereto by their roots whereby the said strip and tongues form substantially a rib of channel shape extending lengthwise of the unit.
- 50 The nature of this invention is now further disclosed with reference to the accompanying drawings in which

Figure 1 is a perspective view showing one construction.

Figure 2 is a perspective view of a detail but to a larger scale than that of Figure 1, of a modification.

Figure 3 is a section on the line III—III of Figure 2.

Figure 4 is a view similar to Figure 2 of a further modification and

Figure 5 is a perspective view showing a unit in its final position for use.

An unit is prepared formed of a sheet of metal A to constitute the under flange of the unit and of a second sheet B of the same surface dimensions to constitute the upper flange of the unit. Tongues C are formed in the material of the upper flange by means of cuts in pairs extending at right-angles to one another in such a manner as to form, for each pair of cuts, four triangular shaped tongues whose tips all meet at the point of intersection of the two cuts and whose roots are arranged as at the sides of a rectangle of which the two cuts constitute the diagonals.

The tongues C are bent down about the lines of their roots C¹ so as all to project from the under-face of the upper flange and the upper flanges B are then placed upon the lower A and the extreme tips C² of the tongues, where they rest upon the lower flange, are spot-welded as indicated by C⁴ or riveted to the lower flange A. If desired, the extreme tip of each tongue may be bent as seen at C³ to lie parallel with the sheet A to afford a better hold when welded.

It will be observed that by the formation described, the material of the upper flange is left to afford what are virtually continuous ribs B¹ of inverted U shape extending lengthwise along the upper flange. Further, that rectangular cells D are formed over the upper surface of the under flange A, and that the triangular shape of the tongues, together with the staggered arrangement of neighbouring cells, causes communication to be afforded between all the cells.

Preferably the tongues on either side of the ribs B¹ are bent to lie at right-angles with the general planes of the flanges, whereas those tongues whose roots are at right-angles to the former are slightly inclined to the said planes so as to give a virtually smaller area to the bottom of each cell than is provided at the top. This modification is illustrated in Figures 2 and

3 where the tongues at right-angles to the flanges are lettered E and those that are inclined are lettered F.

Lengths G of strip metal, rolled to channel section may be slipped into the inverted U-shaped ribs as shown to constitute additional reinforcements. Care is to be taken to keep the said lengths away from contact with the under flange, so that concrete may flow beneath them: care must also be taken not to interfere with communication between cell and cell. Also, perforations G¹ are provided in the strips which register with corresponding perforations G¹ in the plate B¹ so that air can escape therethrough when filling with concrete.

In order to hold the reinforcements G clear of the plate A, small projections as shown at J in Figures 1 and 5 may be formed from the material of the tongues, being bent in such a way as to afford the necessary support. In Figure 1 only two reinforcements G are shown for the sake of clearness in the drawing.

If desired the under plate or flange A may have small tongues formed in a bend to protrude from its lower surface as at K in order to afford a key for plaster applied to the under surface of the plate. These tongues must be made small in order that the apertures left in their formation shall only permit very little concrete to exude therethrough. Such as does exude may be brushed off before it is too hard.

In Figure 5 floor joists L are shown ready in position with a structural beam unit A B supported between them resting upon the lower flanges of the joists and spanning the gap between them. Each unit is dimensioned to have less than half the vertical depth of the finished floor and the several units are placed in position as will readily be understood.

Concrete is then poured upon the units between the joists or girders, the units serving as centering and supporting the concrete. The latter flows into the cells and penetrates everywhere between the upper and lower plates. Struts may be provided, if needed, to support the units temporarily while the concrete is setting.

When the concrete has set, it has become reinforced by the metal of the unit which is thoroughly keyed to the concrete, and even if the underplate rusts off, the reinforcement is sufficient, since the upper plate is dimensioned to ensure this, the prime function of the lower plate being to retain the concrete while it is wet.

For vertical work both plates may be formed with tongues and even for floors this may be done provided the tongues on the lower plate pass up under the ribs B¹ on the upper. This will result in the material of the lower plate A being left un-

disturbed as forming a bottom to each cell whose walls are constituted by the tongues. The tongues on one plate may be riveted or otherwise secured to the tongues on the other instead of being attached direct to the plate itself as shown in the drawings. It is to be observed that between the lengthwise strips B¹ transversely extending strips B² are left which serve to tie adjacent strips B¹ to one another. Further, whereas it is preferable to form the tongues in the manner hereinafter described since this removes no metal from the plate, the tongues may nevertheless be otherwise formed, for example in such a manner as to remove some of the material of the plate in the region surrounded by the tongues before the latter are bent down before the plane of the plate: the tongues may also be other than triangular in shape.

The unit may be used without concrete as a simple slab or beam of light weight and good stiffness.

It will be appreciated that in the construction described in detail above, no metal is cut away but all is utilised.

What I claim as my invention and desire to secure by Letters Patent is:—

1. A reinforcing unit for a reenforced concrete structure comprising in combination two metal plates face to face and spaced apart from one another, one of which plates has in it a plurality of apertures, a metal tongue at each aperture integral at one end with the said plate and formed of material that originally occupied part at least of the said aperture, each tongue projecting toward and directly attached at its other end to the opposed plate and having at least one side spaced away from the apertured plate to provide access from outside the apertured plate through the said apertures past the said tongues to the interspace between the plates, substantially as described.

2. A reinforcing unit for a reenforced concrete structure comprising in combination an upper metal plate and a lower substantially imperforate metal plate arranged face to face and spaced apart one from the other, said upper plate having in it a plurality of apertures, a metal tongue at each aperture integral at one end with the said upper plate and formed of material that originally occupied part at least of the said aperture, each tongue projecting toward and directly attached at its other end to the lower plate and having its two sides spaced away from the apertured plates to provide access from outside the upper plate through the said apertures past the said tongues to the interspace between the plates, substantially as described.

3. A reinforcing unit for a reenforced concrete structure, comprising, in combina-

- tion, two metal plates arranged face to face and spaced apart one from the other, one of which plates has in it a plurality of apertures formed each by slits cut in the metal, 5 the metal between the slits being bent down and constituting tongues each integral at one end with the apertured plate, said tongues being attached each at its other end to the opposed plate.
- 10 4. A reinforcing unit for a reenforced concrete structure, comprising in combination a metal plate having a plurality of apertures through it, groups of four tongues equal in area and triangular in shape projecting from one surface of and integral with the said plate, each of the groups of 15 four tongues constituted by material that originally occupied one of said apertures, and a second metal plate attached directly 20 to the points of the said tongues.
5. A reinforcing unit for a reenforced concrete structure comprising in combination a metal plate having a plurality of apertures through it, said apertures being 25 formed each by slits cut in the metal and arranged to intersect, the metal between the slits being bent down and constituting tongues each integral at one end with the apertured plate, and said apertures being so spaced apart in rows extending longitudinally 30 of the unit as to provide continuous strips extending lengthwise of the unit, and other strips extending transversely from the first and a second metal plate attached directly to the extremities of the said tongues. 35
6. A reinforcing unit for a reenforced concrete structure, comprising in combination a metal plate having a plurality of apertures through it, said apertures being formed each by slits cut in the metal and arranged to intersect, the metal between the slits being bent down and constituting tongues each integral at one end with the apertured plate, and said apertures being so spaced apart in rows extending longitudinally 40 of the unit as to provide continuous strips extending lengthwise of the unit, extending transversely between pairs of lengthwise strips and arranged so as to be staggered in relation to one another, and 45 a second metal plate attached directly to the extremities of the said tongues. 50

In testimony whereof I affix my signature.

RICHARD HAWKE ROGERS.
